UNITED STATES PATENT OFFICE.

AUGUSTUS LEA BRICKNELL, ALGERNON JOSEPH GEORGE BRICKNELL, AND JOHN LEA BRICKNELL, OF CARSHALTON ENGLAND.

INTERNAL-COMBUSTION ENGINE.

1,155,335.

Specification of Letters Patent.

Patented Oct. 5, 1915.

Application filed December 30, 1912. Serial No. 739,349.

To all whom it may concern:

Be it known that we, AUGUSTUS LEA BRICKNELL, ALGERNON JOSEPH GEORGE BRICKNELL, and JOHN LEA BRICKNELL, subjects of the King of Great Britain, and residents of "Waveney," Carshalton, in the county of Surrey, England, have invented certain new and useful Improvements in Internal-Combustion Engines, of which the following is a specification.

The object of the invention is to provide a simple and efficient form of rotary internal combustion engine, and the invention consists in providing intermeshing rotor or gear wheels fitted with a casing on one or both sides thereof, the intermeshing teeth of the wheels forming spaces in which a combustible mixture, supplied to said wheels, is trapped, and compressed by the teeth and fed in parcels from said spaces to a combustion chamber which is constituted by the space formed between the rotor wheels and a portion of the casing.

The invention further consists in providing means for making use of what would otherwise be the waste exhaust pressure which is contained in the several tooth-spaces before they emerge from their housing. This pressure is admitted into what would usually be the combustion chamber of a secondary engine coupled to the one in which the pressure originated, so as to assist in the driving. The engine to which it is so admitted may be adapted to pass its own mixture through its meshing teeth and this, by supplying part of the volume and some heat, will conserve the energy of the aforesaid waste exhaust pressure. This second or compound engine should provide more than enough power to compensate for what may be termed, back pressure resistance in the primary engine.

The invention is illustrated by the diagrammatic drawings of which:

Figure 1 is a cross section of a simple form of low pressure internal combustion engine. Fig. 2 is a longitudinal section of the same. Fig. 3 is a cross section of a modification. Fig. 4 is a cross section of a modified form of engine burning its full capacity of air admitted at normal atmospheric pressure. Fig. 5 is a longitudinal section of a casing with a pocket in the end covers to permit the pressure of the burning

gases to reach the abutment of the meshing wheels where its area is least. Fig. 6 is a cross section of a compound engine. Fig. 7 is a cross section of a double engine. Fig. 8 is a cross section of another construction of engine with pairs of wheels mounted independently in the housing or casing. Fig. 9 is a longitudinal section of a multiple geared wheel engine. Fig. 10 is a cross section on the line X—X of Fig. 9. Fig. 11 is a cross section on the line XI—XI of Fig. 9. Fig. 12 is a cross section of an engine with one large central wheel gearing with smaller wheels on its periphery. Fig. 13 is an end view showing means for reversing the direction of a driven shaft. Fig. 14 is a longitudinal section illustrating a method of cooling a wheel internally. Fig. 15 is a cross section thereof on the line XV—XV, of Fig. 14. Fig. 16 is a cross sectional view showing a construction in which the spaces between the outer periphery of the teeth and the inner wall of the housing are packed, by thin films or sheets of water, and Fig. 17 is a cross sectional view illustrating a method of scavenging or ridding the teeth of exhaust.

Figs. 1 and 2 illustrate a simple form of engine, consisting of a casing or housing *a* in which are mounted the shafts *b* of two meshing, toothed, rotor wheels *c* and *d*, of which one as *c*, delivers the power of the engine, while that marked *d* assists the one marked *c*. The air and fuel are admitted at *e* in the direction of the arrow and are trapped by and compressed between the meshing teeth after which they emerge into the combustion chamber *f*, which may be supplied direct with fuel in the case of volatile fuel.

The fuel being vaporized is ignited at the beginning by a sparking plug or other igniting device *f'* and burns in the combustion chamber *f* with the air and the expanding gases operate upon the teeth to drive the wheels in the direction of the curved arrows, the products of combustion contained in the spaces between each two teeth escaping at the outer ends of the housing as the wheels revolve as shown by the arrows at *g*. The designation, *f'* in succeeding figures of the drawings refers in every case to a sparking plug or other igniting device. This engine is of low pressure, burning less than its

full capacity of air at atmospheric pressure and having no housing on the air inlet or compression side, it creates no back pressure or resistance. After ignition has once taken place, the fuel in the combustion chamber *f* burns continuously and the current may be cut off from the sparking plug, but if the combustion be intermittent, it follows that the sparking plug is arranged to ignite the charge intermittently as and when required.

Fig. 3 shows another form of engine in which air is admitted at normal atmospheric pressure, between the upper and lower housings *h* and *a* and passes around in parcels formed by the spaces between the teeth of the wheels *c* and *d* bounded externally by the upper housing *h* in close proximity to the wheels whence it passes to the abutment while fuel is admitted from the ports *i* to the same teeth, whereby a full supply of combustible mixture is brought in parcels in the spaces between the teeth and compressed by them and delivered to the combustion chamber *f*. In this construction, the housing *h* is carried to an apex in the neighborhood of the meshing teeth of the wheels so that, in this and in every other construction in which the ingoing teeth are housed, the whole of each parcel of air, whether accompanied by fuel or not, contained between the teeth, as they approach the point of meshing, is retained within the casing, but as the intermeshing teeth approach each other, they reject a certain portion of each parcel and these rejected portions accumulate, with the result that a certain amount of back-pressure or resistance is produced in that part of the housing or casing until it is automatically relieved by the teeth, trapping by their meshing contact at the abutment, and so carrying away, as much accumulation into the combustion chamber as the incoming parcels provide for. In like manner and in cases where very quickly combustible fuel is used, the casing on the combustion chamber side may be carried as nearly to an apex as will leave room enough, and therefore time enough, for proper combustion and expansion.

The housing is open between the ends of the upper housing *h* and the lower housing *a*. The exhaust takes place at *g* on each side and shields *k* have the effect of directing the exhaust to a great extent away from the wheels. To scavenge the spaces between the teeth there are provided pipes *l* which deliver sheets or jets of compressed air on to the teeth. To cool the wheels, sheets or jets of water are delivered on to the teeth of the wheels by pipes *m*.

According to a modification, slotted or perforated pipes *n* are provided for the supply of compressed air to the spaces between the teeth of the wheels and so as to mingle with the fuel entering at *i*.

The construction of engine shown in Fig. 4 somewhat resembles that illustrated in Fig. 3, but the internal contours of the upper and lower housings are identical. Air enters at the openings *e* and fuel is admitted at *o*, so that air and fuel pass around in parcels in the spaces between the teeth of the wheels *c* and *d* and the upper housing *p* to the compression chamber *q*, and thence to the combustion chamber *f*, but back pressure or resistance is created as previously described inasmuch as a part of each parcel of air or mixture entering between the teeth passing into the compression chamber *q* is not retained, but goes back into the said chamber until the pressure in that chamber becomes sufficiently high to insure the normal amount of air or mixture at the increased pressure being delivered between the meshing teeth and past their abutment into the combustion chamber *f*. The teeth of the wheels of this engine are kept cool by sheets or sprays of water delivered from the slotted or perforated pipes *r* and air may be similarly delivered for scavenging purposes by the pipes *s*, shields or walls *t* being provided to prevent the water thrown off from the teeth by centrifugal force from mingling with the air admitted at *e* or the exhaust escaping at *g*. Air may also be admitted by the pipes *u*. The engine here shown may also be made to reverse its direction of rotation by using the pipes in the lower casing *a* corresponding to the fuel pipes *o* and if desired the air pipes *u* and by employing the compression chamber *q* as the combustion chamber and the combustion chamber *f* as compression chamber and obviously one or the other of the air spraying pipes *s* at each end is supplied with compressed air according to the direction of rotation, or both may be supplied or additional pipes may be employed at or near this place.

As in the previous construction the exhaust takes place on each side at *g*. Obviously in this case as in all other cases the housing *a*, *p*, may be made hollow or in the form of a water jacket to keep the parts cool.

The construction shown in Fig. 5 illustrates a pocket or recess *v* in the end plate or plates *w* whereby the pressure of the burning gases in the combustion chamber may be added to the trapped gases on the combustion side of the abutment, either to further compress them or to ignite them and thus prevent the opposition of the abutment by any but its smallest area. Conversely, the effect of the larger area of the abutment on the compression side at the moment of trapping is useful in greatly counteracting the back pressure resistance. Naturally the pockets must not extend beyond the line of abutment or the combustion chamber would be in direct communication with the compression chamber. It will be evident that if

this engine is to be made reversible, the said by-passes or pockets must be closable in any convenient manner or they may be duplicated on the other side of the abutment and so arranged that one or the other is closed according to the direction of running of the engine.

As shown in Fig. 6, the gases from the combustion chamber of the primary engine, shown above, emerge from the combustion chamber *f* in the form of isolated charges contained between the teeth of the rotor wheels *c* and *d* and then pass by the conduits *x* into the combustion or equivalent chamber *y* of the secondary engine below. In cases where it is desired to compress the parcels of air or mixture in the primary engine, the air or mixture to be added is conveyed from the compression chamber *g'* of the secondary engine to the spaces between the teeth of the wheels of the other or primary engine, while the said teeth are in their housing and before they reach the compression chamber *g* of the primary engine, by means of pipes or passages *j* so that parcels of compressed air or mixture are eventually carried into the compression chamber of the primary engine whereby the resistance to compression by the secondary engine is minimized because it compresses the said parcels before they encounter resistance due to pressure in the primary compression chamber *g*. In this latter example, the air is compressed above atmospheric pressure and the power of the engine and the so-called back pressure or resistance are both proportionately higher than in the engines described with reference to Figs. 3 and 4.

The construction shown in Fig. 7 comprises internally symmetrical upper and lower housings *z* and 1, upper combustion chamber 2 and lower combustion chamber 3, one pair of geared wheels 4 and 5 above, and meshing respectively with these, another pair of geared wheels 6 and 7 below, leaving a space or chamber 8 in the middle, in which appears nothing but teeth, except the end plates or covers 9, which inclose the space and carry the bearings of the four wheels. Air is admitted and mixture may be admitted to the central chamber at 10. The back pressure or resistance is rendered nugatory in this construction, because it will be evident that whatever air or mixture is brought through the meshed teeth at 10 into the central chamber 8, will be carried by the meshed teeth of 4 and 5, and 6 and 7, respectively into their respective combustion chambers 2 and 3, and that neither attenuation nor compression of the contents of the central chamber 8 will ensue, but it will remain at normal atmospheric pressure or practically so. But if compressed air or mixture be admitted to the central chamber through the end plates 9 and not through any teeth,

such fluid will not exert any retarding effect upon the engine because the resistance set up by the back pressure upon the teeth of the top pair of wheels 4 and 5 and upon the teeth of the lower pair of wheels 6 and 7 which are running outward from the central chamber is balanced by the corresponding driving effect it exerts upon the meshed teeth of the wheels 4 and 6, and 5 and 7, which are running inward toward the central chamber. The action of compression upon the teeth being therefore balanced, this compression is effected by means of air compressed by a secondary engine or by any other suitable means. An engine of this type is either a double low pressure engine if supplied with air and fuel or mixture through the teeth of the wheels 4 and 6, and 5 and 7, or it may be compounded, in which case the exhaust gases from between the teeth of the primary engine, before they emerge from their casting enter the combustion chamber or chambers of the secondary engine.

In the construction shown in Fig. 8, one pair of meshing wheels 12 and 13 is mounted over another pair 14 and 15 respectively and there is sufficient space between the pairs to allow of one common combustion chamber 16 housed at 17 and 18 to fit both pairs. The engine may be low pressure without back pressure or resistance if the entering teeth are not housed above and below or of normal pressure with back pressure or resistance if they are housed above at 19 and below at 20 and of more than normal pressure if the parcels are compressed, as is the case when the useful exhaust gases are delivered from a primary engine to a secondary or compound engine as shown for example in Fig. 6.

Figs. 9 to 11 show a modification of the double engine previously described. This modification is constructed so as to leave the ends of the central space 21 open and to house the pairs of wheels 22, 23, and 24, 25, and 26, 27, with a housing 28 which is provided with apertures 29, 30, and 31, by which air or mixture, freely passing through the central space, will reach the incoming teeth of adjacent wheels and be from thence carried in the spaces between those teeth and their housing to and among the engaging teeth which feed their combustion chambers 32, 33, and 34, formed by the external housings 35, 36, and 37. Scavenging will have been effected by the meshing of the uncovered inwardly running teeth. In engines where more than one pair of wheels are engaged, axial pressure is provided for by furnishing the ends of every shaft with hardened rollers 38 (Figs. 9 and 11) which, by running with their faces in contact, counteract and balance either wholly or partly the axial pressure which otherwise would be exerted upon the bearings. These hardened

rollers will revolve without friction with their wheel axles and may revolve in oil chambers 39 and 40 situated at each end of the housing.

- 5 In the construction illustrated in Fig. 12, one central toothed wheel 41 serves as the second member of the pair with two, three, four, or more toothed wheels situated around it and geared with it. In this example 10 there are four such wheels 42, 43, 44 and 45. This central wheel 41 is usually larger than those which engage with it and therefore while the number of their revolutions may be high and the peripheral speed may be 15 high, the number of revolutions of the central gear common to all may be low as is often necessary. If each small member be housed on one and the same side for combustion, this engine will not be reversible 20 and will be of low pressure without back pressure or resistance as with some of the engines hereinbefore described, but if as shown there be a chamber housed on each side of each small member, then each small 25 member of this engine will be provided with a compression chamber 46 and a combustion chamber 47, air or fuel or both entering in parcels between the toothed wheels and the housing as indicated by the arrows pointing 30 toward the engine and the exhaust being carried in the spaces between the teeth of the toothed wheels and the housing 48, and finally escaping partly by the openings 49 and partly by the openings *q* as indicated by 35 the arrows pointing outward. Obviously, if the chambers 47 be used as compression chambers and the chambers 46 as combustion chambers, the engine will be reversible as described and will have the other features 40 attributed to other of the engines herein described as will be readily understood. Reversing of machinery when driven by such of these engines as are not reversible may be effected by many well known means, 45 such as electric, hydraulic, and pneumatic transmission or by mechanical reversing clutches, or for example such engines may according to this invention be adapted for such reversing by fitting the shaft 50 of a 50 "driver" wheel as shown in Fig. 13, with a pinion 51 and the shaft 52 of another wheel with a pinion 53 and providing such pinions with magnetic or friction clutches or shifting mechanical clutches diagrammatically indicated at 54 and 55 so that only one or 55 other of these pinions may be coupled to its shaft at a time. Both these pinions engage, preferably by double or herring-bone helical teeth, with a gear wheel 56 fixed to a main shaft 57 intended to be driven. Only the pinion which is held to its shaft will drive, and the other will revolve idly. By disconnecting the driving pinion an instant before connecting the idler pinion, the machinery 60 will be reversed without reversing the en-

gine. In large installations, hydraulic or other brakes may be applied in the interval to check momentum of the driven part. But in those engines which are reversible in themselves very simple means are provided by so constructing the housing as aforesaid and as shown, for instance in Fig. 4, that it constitutes two chambers one above and one below or one on each side of the intermeshing teeth of the rotor wheels, each of which chambers is capable of being used alternately to the other as a combustion chamber for the purpose of reversing the engine.

It will be seen from the above description that in cases where unbalanced back pressure or resistance is produced one of these chambers has been a compression chamber, but that in cases where it is intended that such pressure shall not arise in these chambers, they must be freely open to the atmosphere by means of relief cocks 70, as also shown in Fig. 4 for example or otherwise, till their use as combustion chambers is required and in all cases of this latter kind every combustion chamber must be so provided. The fire, being constantly fed from the meshed teeth, is continuous in the combustion chamber and this continuous fire, which is continuously fed without occasioning any re-active influence or resistance from the pressure of combustion, is a feature of the invention. The transmission of such fire from the combustion chamber to a compression chamber may as shown in Fig. 4, be effected by a pipe or by-pass passage 71 external 100 to the chambers, which passage may be momentarily opened by means of a cock 72, thus affording a ready means of igniting the contents of the chamber entered, which thus becomes in its turn the combustion 105 chamber and reverses the engine. When back pressure is present in the chamber entered by the fire it will have a very powerful effect in reversing, and if too powerful, relief may be afforded by a simultaneously 110 opened relief cock or by a safety-valve 73 operative only in such eventuality as also shown in Fig. 4. In those cases where the chamber entered contained no back pressure, such as the chambers which have been 115 freely open by relief cocks 70 as has been described, the entering pressure should be sufficient to effect reversal, but in cases where it is not so, a little of the fuel or of some superior fuel may be injected, as an 120 aid, into the inclosed air till reversal occurs. The relief cocks in the vacated combustion chamber must be (momentarily in the case 125 of engines with back pressure) opened at the closing of the by-pass. The revolving toothed wheels may, as shown in Figs. 14 and 15, be also well cooled, internally by admitting water through passages 58 in the centers of their axles and by radial ports 59 to chambers 60 formed by turning an 130

annular groove or grooves around the main body of the wheel, before its outer ring 61 (in which the teeth have been cut or will afterward be cut) has been fixed upon it. 5 All the grooves should communicate with each other, and some holes 62 drilled into the chamber at the ends of the wheels will emit the centrifugally forced water as they pass by a small pocket or recess at their ends 10 which allows for its escape. Thus a current is maintained through the chambers automatically and the pressure contact of the water at these emission holes will further cool the insides of the end covers as the 15 water passes around in the holes on its way to escape. Thus both outside and inside cooling is very thoroughly and simply effected. Inside cooling is still further promoted by the method of packing the peripheral ends of the revolving teeth as shown 20 in Fig. 16. This is effected by thin sheets of water introduced from apertures in pipes 63 or other suitable apertures in or contiguous to the combustion chamber, and arranged so that fine jets or a thin sheet of 25 water shall be directed toward the very small space left between the ends of the teeth and their housing as they enter the housing on their way from the combustion 30 chamber. The thin sheet of water will thus line the inside of the housing till it arrives at the outlet which it will leave with the exhaust. This sealing water must of course be delivered at a pressure somewhat exceeding 35 the combustion chamber pressure, but the volume of water is relatively very small so that a small pump will suffice to supply the water. When reversing the engine this water may, by the same act, be diverted by 40 suitable means into similar pipes in the temporary combustion chamber as will be readily understood.

Fig. 17 shows a method of scavenging the exhaust gases from the spaces between the 45 teeth of the wheels and it consists of a small toothed wheel or wheels 64 at each end of the engine, the teeth of which meshing with the wheels *c*; *d*, expel the gas from said spaces and by tending to create a vacuum 50 as the tooth of one wheel leaves the corresponding space between the teeth of the other wheel, aids in the supply of fresh air to the engine. When the fuel is of a suitable character for feeding it into the parcels of 55 air between the teeth it is preferable to do so, but this cannot of course be done when the spaces between the teeth are not housed, and even in cases where they are housed and lead to a chamber which is more or less 60 opened by relief cocks it is preferable to feed the fuel in this manner unless it be of a sufficiently volatile character to occasion a loss of its gas value which would pass out through the cocks. But if it be so such fuel 65 must be injected into the combustion cham-

ber as spray or jet to meet the air which in all cases arrives in the combustion chamber from the meshed teeth. But in cases in which the combustion chamber is below the abutment and the downward running teeth 70 above it are naked or only splash-shielded, such oils or other fuels, as are not too volatile, may be simply dropped upon the meshing teeth or, when the combustion chamber is above, may be projected upward to them, 75 and so will in both cases, pass with the air among the meshed teeth to the fire.

In cases where more than one fire is used in an engine or a series of engines, pipe communication may be established between them for the purpose of equalizing the fire pressure if desired, and also for the purpose of transmitting flame from the firing of one so as to fire others.

Although various ways of carrying out this invention have been described, it should be clearly understood that it may be carried out otherwise in many particulars without departing from the essentials of the said invention.

I claim—

1. A rotary internal combustion engine, comprising in combination, a casing, intermeshed toothed rotor wheels mounted in said casing, a combustion chamber constituted by the space formed between the rotor wheels and a portion of said casing, means for supplying combustible mixture to said combustion chamber between the intermeshing teeth of said rotor wheels, means for igniting the combustible mixture, and exhaust outlets from said casing for the products of combustion, substantially as set forth.

2. A rotary internal combustion engine comprising in combination, a casing, intermeshed toothed rotor wheels mounted in said casing, a combustion chamber constituted by the space formed between the rotor wheels and a portion of said casing, means for supplying air to said combustion chamber between the intermeshing teeth of said rotor wheels, means for supplying fuel to said combustion chamber, means for igniting the combustible mixture of fuel and air, and exhaust outlets from said casing for the products of combustion, substantially as set forth.

3. A rotary internal combustion engine comprising in combination, a casing, intermeshed toothed rotor wheels mounted in said casing, a combustion chamber constituted by the space formed between the rotor wheels and a portion of said casing, means for supplying combustible mixture to said combustion chamber between the intermeshing teeth of said rotor wheels, means for igniting the first supply of combustible mixture fed to the combustion chamber, continuous combustion of subsequent supplies of combustible mixture being maintained by

90

the burning gases in the combustion chamber, and exhaust outlets from said casing for the products of combustion, substantially as set forth.

5 4. A rotary internal combustion engine comprising in combination, a casing, intermeshed toothed rotor wheels mounted in said casing, a combustion chamber constituted by the space formed between the rotor 10 wheels and a portion of said casing, means for supplying air to said combustion chamber between the intermeshing teeth of said rotor wheels, means for supplying fuel to said combustion chamber, means for igniting the first supply of combustible mixture of fuel and air fed to the combustion chamber, continuous combustion of subsequent supplies of fuel and air being maintained by the burning gases in the combustion 15 chamber, and exhaust outlets from said casing for the products of combustion, substantially as set forth.

5. A rotary internal combustion engine comprising in combination, a casing, intermeshed toothed rotor wheels mounted in said casing, a combustion chamber constituted by the space formed between the rotor 20 wheels and a portion of said casing, means for supplying combustible mixture to the spaces between the teeth of the rotor wheels as said teeth move toward the combustion chamber, means for igniting the combustible mixture in said combustion chamber, and exhaust outlets from said casing for the products of combustion, substantially as set forth.

6. A rotary internal combustion engine comprising in combination, a casing, intermeshed toothed rotor wheels mounted in said casing, a combustion chamber constituted by the space formed between the rotor 25 wheels and a portion of said casing, means for supplying combustible mixture to said combustion chamber, means for igniting the combustible mixture in said combustion chamber, and outlets for the exhaust of the products of combustion from said casing, direct communication between said combustion chamber and exhaust outlets being prevented by the intervening teeth of the rotor wheels, substantially as set forth.

7. A rotary internal combustion engine comprising in combination a casing, intermeshed toothed rotor wheels mounted in said casing, a combustion chamber constituted by the space formed between the rotor 30 wheels and a portion of said casing, means for supplying combustible mixture to said combustion chamber, means for igniting the combustible mixture in said combustion chamber, and outlets for the exhaust of the products of combustion from said casing, said products of combustion being carried 35 to the exhaust outlets in the spaces between

the teeth of the said rotor wheels, substantially as set forth.

8. A rotary internal combustion engine comprising in combination, a casing, intermeshed toothed rotor wheels mounted in 70 said casing, a combustion chamber constituted by the space formed between the rotor wheels and a portion of said casing, means for supplying combustible mixture between the teeth of the rotor wheels, the combustible mixture being compressed in the spaces between the intermeshing teeth, means for igniting the combustible mixture in said combustion chamber and exhaust outlets from said casing for the products of combustion, substantially as set forth.

9. A rotary internal combustion engine comprising in combination, a casing, intermeshed toothed rotor wheels mounted in 75 said casing, a combustion chamber constituted by the space formed between the rotor wheels and a portion of said casing, means for supplying air to said combustion chamber between the intermeshing teeth of said rotor wheels, such air being compressed in 80 the spaces between the intermeshing teeth, means for supplying fuel to said combustion chamber, means for igniting the combustible mixture of fuel and air fed to the combustion chamber, and exhaust outlets from said casing for the products of combustion, substantially as set forth.

10. A rotary internal combustion engine comprising in combination, a casing, intermeshed toothed rotor wheels mounted in 85 said casing, a combustion chamber constituted by the space formed between the rotor wheels and a portion of said casing, means for supplying combustible mixture to the spaces between the teeth of the rotor wheels as said teeth move toward the combustion chamber, means for igniting the combustible mixture in said combustion chamber and openings at either side of said casing, said 90 openings permitting of both the inlet of air for supporting combustion and the exhaust of the products of combustion from the combustion chamber, substantially as set forth.

11. A rotary internal combustion engine, comprising in combination, a casing, intermeshed toothed rotor wheels mounted in 95 said casing, a compression chamber constituted by the space formed between the rotor wheels and one portion of the casing, a combustion chamber constituted by the space formed between the rotor wheels and another portion of the casing, said compression and combustion chambers being on opposite sides of the intermeshing teeth of the rotor wheels, means for supplying combustible mixture to said compression chamber from whence the combustible is carried to the combustion chamber by the teeth of the rotor wheels, means for igniting the combustible mixture, and exhaust outlets from 100

the casing for the products of combustion, substantially as set forth.

12. A rotary internal combustion engine comprising in combination, a casing, intermeshed toothed rotor wheels mounted in said casing, a chamber constituted by the space formed between the rotor wheels and one portion of the casing, another chamber constituted by the space formed between the 10 rotor wheels and another portion of the casing, said chambers being on opposite sides of the intermeshing teeth of the rotor wheels, means for supplying combustible mixture to either of said chambers whereby 15 either one of said chambers may constitute a combustion chamber, means for igniting the combustible mixture, and exhaust outlets from the casing for the products of combustion, substantially as and for the purpose set forth.

13. A rotary internal combustion engine comprising in combination, a casing, intermeshed toothed rotor wheels mounted in said casing, a combustion chamber constituted by the space formed between the rotor 25 wheels and a portion of said casing, means for supplying combustible mixture to said combustion chamber, means for igniting the combustible mixture, exhaust outlets from 30 said casing for the products of combustion, the latter being carried in the spaces between the teeth of the rotor wheels to the exhaust outlets, and pipes for subsequently delivering fluid onto said rotor wheels, substantially as and for the purpose set forth.

14. A rotary internal combustion engine comprising in combination, a casing, intermeshed toothed rotor wheels mounted in said casing, a combustion chamber constituted by the space formed between the rotor 40 wheels and a portion of said casing, means for supplying combustible mixture to said combustion chamber, means for igniting the combustible mixture, exhaust outlets from 45 said casing for the products of combustion, the latter being carried in the spaces between the teeth of the rotor wheels to the exhaust outlets, and means for subsequently scavenging the teeth of the rotor wheels, substantially as set forth.

15. A rotary internal combustion engine comprising in combination, a casing, intermeshed toothed rotor wheels mounted in said casing, a combustion chamber constituted by the space formed between the rotor 55 wheels and a portion of said casing, means for supplying combustible mixture to said combustion chamber, means for igniting the combustible mixture, exhaust outlets from 60 said casing for the products of combustion, and means for cooling said rotor wheels, substantially as set forth.

16. An internal combustion engine com-

prising in combination, a casing, intermeshed toothed rotor wheels mounted in 65 said casing, a combustion chamber constituted by the space formed between the rotor wheels and a portion of said casing, means for supplying combustible mixture to said combustion chamber, means for igniting the 70 combustible mixture, exhaust outlets from said casing for the products of combustion, the latter being carried in the spaces between the teeth of the rotor wheels to the exhaust outlets, and deflecting devices at 75 said outlets for deflecting the products of combustion away from the rotor wheels, substantially as set forth.

17. An internal combustion engine, comprising in combination, a casing, intermeshed toothed rotor wheels mounted in said casing, a combustion chamber constituted by the space formed between the rotor 80 wheels and a portion of said casing, means for supplying fuel to said combustion chamber, openings in the sides of said casing for the admission of air and for the exhaust of products of combustion, means for igniting the combustible mixture of air and fuel in the combustion chamber, means for delivering a cooling medium onto said rotor wheels at said openings, and deflecting devices for preventing the cooling medium from intermingling with the ingoing air or the exhaust, substantially as set forth.

18. A rotary internal combustion engine comprising in combination, a casing, a pair of intermeshed toothed rotor wheels mounted in said casing, a combustion chamber constituted by the space formed between a 100 portion of said casing and said rotor wheels, means for supplying combustible mixture to said combustion chamber between the intermeshing teeth of said rotor wheels, means for igniting the combustible mixture and exhaust outlets from said casing for the products of combustion, substantially as set forth.

19. A rotary internal combustion engine, comprising in combination, a casing, a plurality of intermeshed toothed rotor wheels, combustion space formed between the rotor wheels and the casing, means for supplying combustible mixture to said combustion space between the intermeshing teeth of said 110 rotor wheels, means for igniting the combustible mixture, and exhaust outlets from said casing for the products of combustion, substantially as set forth.
